PAPER WEB TENSIONING MECHANISM FOR
PRINTING PRESSES

Gilbert V. Anderson, Philadelphia, and Wesley E. Conklin, Wyncote, Pa., assignors to William F. Fischer, Philadelphia, Pa.

Application January 15, 1936, Serial No. 59,164

3 Claims. (CL 242—75)

This invention relates to mechanism useful in connection with printing presses and the like to maintain paper webs under tension incident to being withdrawn from supply rolls; and it has reference more particularly to tensioning mechanism of the type wherein the drag on the web is obtained as a consequence of the imposition of restraint upon the supply roll by a member in pressure contact with the roll periphery.

With tensioning mechanism of the type specifically referred to, as heretofore constructed, difficulty has been experienced in maintaining the tension on the paper web constant due to the disturbing influence, upon the restraining member, of the gradually decreasing diameter of the paper roll as the supply thereon dwindle in satisfying the demands of the press.

Our invention is directed toward overcoming the above mentioned drawback; that is to say, we aim to make possible the maintenance of a constant tension on the web throughout the unwinding period of the supply roll. This desideratum we realize in practice, as hereinafter more fully disclosed, through provision of automatic means whereby the pressure on the restraining member is varied compensatively with the decrease in the diameter of the supply roll as the web is drawn therefrom.

A further aim of our invention is to provide, in web tensioning mechanism having the foregoing attributes, manually adjustable control means whereby any desired degree of tension may be predetermined in the traveling paper web.

Other objects and attendant advantages will appear from the detailed description which follows of the attached drawings, wherein Fig. I is a fragmentary and more or less diagrammatic view, in longitudinal section, of a printing press embodying our improved web tensioning means; and

Fig. II is a view of the organization as it appears when observed from the right of Fig. I.

With more detailed reference to these illustrations, 1 indicates the supply roll from which the paper web 2 is continuously drawn in the direction indicated by the arrow in Fig. I incident to printing, the ends of the shaft 3 of said roll being journaled for free rotation in open bearings 4 on brackets 5 extending rearwardly from the side frames 6 of the printing press.

The mechanism which we have devised for maintaining a predetermined uniform tension on the paper web 2 as it is being delivered to the printing instrumentalities of the press, includes a restraining leverage member which is com-

prehensively designated by the numeral 7, and which imposes a braking force upon said roll. In the present instance, this restraining member constitutes a part of a means associated with the press for bringing fresh paper supply rolls up to speed in readiness to be substituted for exhausting rolls in a manner well known in the art and which need not therefore be dwelt upon here. As shown, the restraining member 7 comprises a frame consisting of a plurality of spaced arms 8, which, at their upper ends, are secured to a transverse shaft 9 having journal support in bearings 10 on the side frames 6 of the press; and a connecting cross bar 11 joining said arms at their lower ends. Free on the shaft 9 are pulleys 12 which are respectively coordinated, through a corresponding number of normally idle endless flexible belts 13 of leather or the like, with pulleys 15 carried by bearing yokes 16 whereof the shanks 17 are slidably engaged in apertures in the cross bar 11. Compression springs 18 interposed between heads 19 at the lower ends of the yoke shanks 17 and the bottom surface of the cross bar 11, serve to keep the belts 13 taut. Respectively associated with the free pulleys 12 on the shaft 9 are gear wheels 20 which are adapted to be motivated at the proper time by means not illustrated to drive the belts 13 and thereby effect rotation of the roll 1 by contact therewith to bring it up to speed as above explained.

The web tensioning mechanism of our invention further includes an electric device in the form of a torque motor with an incorporated speed reducing unit, conventionally represented at 21, said motor being secured, at a suitable location, to one of the side frames 6 of the printing press as shown in Fig. II. Affixed to the shaft 22 of the motor 21 is a miter gear pinion 23 that meshes with a companion miter gear pinion 24 at one end of a short countershaft 25 journaled in a fixed bearing 26 adjacent said motor. A sprocket wheel 27 at the opposite end of the countershaft 25 is connected, by means of a chain 28, with a larger sprocket wheel 29 at one end of the transverse shaft 9 from which the belt carrying frame is suspended. By action of the motor 21, torque is induced in the shaft 9 in the direction indicated by the arrow in Fig. I so that the belts 13 are caused to continuously bear against the outer surface of the roll 1.

In order to vary the pressure of the belts 13 on the roll 1 gradually, i. e. to increase it compensatively with decrease in the diameter of said roll as the supply on the latter dwindle, as well

as compensatively with attendant change in the leverage distance of the points of tangency between said belts and the roll periphery, we have provided means for automatically governing the supply of electric current to the motor 21. As shown, this means comprises a variable resistance in the form of a rheostat 38 whereof the contact finger 31 is moved, through coordination of its shaft 32 by a sprocket chain 33, with the torque shaft 8 at the end opposite to that occupied by the sprocket wheel 28, see Fig. II. There is also provided a manually adjustable rheostat 34 which is in series with the automatically actuated rheostat 38, and which serves as a master control whereby the mechanism can be set to maintain any desired degree of drag or tension on the paper web 2. The wiring connections between the motor 21, the rheostats 38, 34 and the power line 35 may otherwise be as shown in Fig. I.

The operation of the mechanism is as follows:

Let it be assumed that the printing press is in operation, and that the paper web 2 is being continuously drawn from the supply roll 1 in the direction indicated. By the clockwise torque induced in the shaft 8, the belts 13 are maintained in idling pressure contact with the periphery of the roll 1, and at the same time caused to follow up on the latter as it decreases in diameter, with attendant turning of said shaft. Through the sprocket chain connection 33, the contact arm 31 of the rheostat 38 is concurrently shifted clockwise in Fig. I to gradually decrease the resistance in the circuit to the motor 21, with the result that the torque induced in the shaft 8 is increased and this in turn followed by a corresponding increase in the pressure of the belts 13 upon the roll 1. It will thus be seen that, in this way, the restraint upon the supply roll 1 is varied compensatively with decrease in the diameter of the latter and with the change in the effective leverage length of the member 1, to the advantage that the web 2 is maintained under substantially constant tension (determined by setting of the manually adjustable rheostat 34) throughout the entire period of unwinding of said roll.

By reversing the motor 21 upon near exhaustion of the roll 1, the belt carrying frame 7 can be retracted in preparation for the substitution of a fresh supply roll. The motor 21 may moreover be utilized to maintain the belts 13 in contact with the fresh supply roll as the latter is brought

up to speed by driving of said belts through the gears 29 incident to the substituting cycle of the change mechanism in a known manner.

The web tensioning mechanism herein specifically shown and described is of course to be considered as typical of other forms in which our invention may be embodied within the scope of the appended claims.

Having thus described our invention, we claim:

1. Paper tensioning mechanism for printing presses and the like including a shaft; an arm secured to the shaft; a restraining member carried by the arm and adapted to bear upon the peripheral surface of the supply roll from which the web is continuously drawn in satisfying the demands of the press; an electric torque motor coordinated with the shaft and effective to keep the restraining member in pressure contact with the roll; and a rheostat automatically actuated from said shaft to vary the flow of electric current to the motor as the diameter of the roll decreases and thereby maintain uniform tension on the web throughout the unwinding period of said roll.

2. Paper tensioning mechanism for printing presses and the like according to claim 1, including an auxiliary manually-operable rheostat in series with the first-mentioned rheostat whereby the electric current flow can be regulated to predetermined the degree of tension which is to be maintained on the web.

3. Paper tensioning mechanism for printing presses and the like including a shaft; an arm secured to the shaft; a restraining member carried by the arm and adapted to bear upon the peripheral surface of the supply roll from which the web is continuously drawn in satisfying the demands of the press; electric means for inducing torque in the shaft to keep the restraining member in pressure contact with the roll; electric means actuated from the shaft for automatically controlling the torque inducing means for maintenance of uniform tension on the web throughout the unwinding period of the roll; and manually-operable auxiliary electric means for regulating the electric current flow and thereby predetermining the degree of tension which is to be maintained on the web by the torque inducing means.
